US0D1054412S

(12) **United States Design Patent** (10) Patent No.: **US D1,054,412 S**
(45) Date of Patent: ** Dec. 17, 2024

(54) **COMPUTER**

(71) Applicant: **Siemens Aktiengesellschaft**, Munich (DE)

(72) Inventors: **Jan Andersson**, Erlangen (DE); **André Diekneite**, Neustadt an der Aisch (DE); **Sebastian Drosdek**, Erlangen (DE); **Stephan Hühne**, Wilhermsdorf (DE); **Andreas Morlock**, Pfinztal (DE); **Nils Wischermann**, Karlsruhe (DE); **Li Wei Wu**, Amberg (DE)

(73) Assignee: **SIEMENS AKTIENGESELLSCHAFT**, Munich (DE)

(**) Term: **15 Years**

(21) Appl. No.: **29/839,998**

(22) Filed: **May 25, 2022**

(30) **Foreign Application Priority Data**

Nov. 30, 2021 (EM) 008781876

(51) LOC (14) Cl. **14-02**

(52) U.S. Cl.

USPC **D14/315**

(58) **Field of Classification Search**

USPC D14/315-329, 341, 345, 371, 376, D14/432-433, 439-440; D21/324, D21/329-330, 332, 515; D24/160, D24/185-186

CPC G06F 1/1616; G06F 1/1626

See application file for complete search history.

(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a front, top and right-side perspective view thereof. The broken lines in the drawings illustrate portions of the computer that form no part of the claimed design.

1 Claim, 7 Drawing Sheets
